UNITED STATES PATENT OFFICE.

JAMES S. WARNER, OF NEW PHILADELPHIA, OHIO.

KEY-POUCH.

1,194,796.

Specification of Letters Patent. Patented Aug. 15, 1916.

Application filed November 23, 1915. Serial No. 63,076.

To all whom it may concern:

Be it known that I, JAMES S. WARNER, a citizen of the United States, residing at New Philadelphia, in the county of Tuscarawas and State of Ohio, have invented certain new and useful Improvements in Key-Pouches, of which the following is a specification.

This invention relates to key pouches or books, and has for one of its objects to increase the efficiency and utility of devices of this character.

Another object of the invention is to provide a device of this character whereby the coacting pocket holding and key supporting fastening devices are entirely concealed and protected when the device is closed.

With these and other objects in view, the invention consists in certain novel features of construction as hereinafter shown and described, and then specifically pointed out in the claims; and in the drawings illustrative of the preferred embodiment of the invention.

25 Figure 1 is a perspective view of the improved device closed with one of the keys and the name plate or identification tag extended; Fig. 2 is a longitudinal sectional view; Fig. 3 is a transverse section; Fig. 4 is a perspective view of the improved device partly open.

The improved device is constructed from a single strip of flexible material such as leather or the like with one portion folded back and forth upon itself to form a plurality of pockets indicated at 10 open at the ends and likewise open at opposite sides, that is to say one-half of the pockets open toward one side of the device and the remaining alternate pockets at the opposite side. The remaining portion of the strip of material constitutes a relatively long flap, represented as a whole at 11.

40 Inserted through portions of the folded or pocket portion of the device from one side are tubular members 12 internally threaded, and inserted through the remaining pocket portion of the device from the opposite side are threaded pins 13. The tubular members 12 are located relatively near the ends of the pockets and each provided with an enlarged head 14, while the pins 13 are likewise provided with enlarged heads 15, the heads being preferably provided 45 with screw driver receiving recesses to en-

able them to be rotated. By this means the pocket devices are firmly connected and at the same time the length of the fastening devices may be adjusted as required. The tubular portions 12 and the pin 13 constitute pivots upon which the keys or other articles are mounted for rotation, the keys being indicated conventionally at 16. Any required number of the folds may be formed to constitute a corresponding number of 65 pockets, and it is not desired, therefore, to limit the device to any specific number of pockets. For the purpose of illustration the device is shown with seven pockets, three opening toward one side and four opening 70 toward the other side with each pocket provided with a separate key or the like. Preferably one of the pivoted members will be in the form of a name plate or identification tag indicated at 17 and containing the address of the owner of the device. The flap 11 is of sufficient length to fold over one side and both edges of the folded portion of the device and likewise fold over the root or inner terminal portion of the flap, as indicated at 18. By this means the folded portion of the device is entirely concealed and covered by the flap, which likewise covers and conceals the heads 14-15 as indicated more clearly in Fig. 3.

75 A device of the glove fastening construction will preferably be employed to connect the flap to the adjacent portion of the folded part of the device, as indicated conventionally at 19, the outer terminal of the fastener 90 being the only metal portion of the device which is visible.

The terminal 18 of the flap extending over the root or inner terminal of the body of the flap is an important feature of applicant's device and materially increases the efficiency and utility, as no danger exists of the metal terminals 14 of the pivot devices coming in contact with the pocket of the 95 owner of the device.

100 The improved device is simple in construction, can be inexpensively manufactured of any required size and of any suitable material, and readily adapted to keys of various sizes and forms and enables the owner of the device to select the required key after a slight practice without the necessity for looking at the key, thus enabling the device to be used in the dark as well as in the light.

Having thus described the invention what is claimed as new is:—

A device of the class described constructed from a strip of flexible material a portion 5 of which is folded into a plurality of pockets each open at the ends and along one side and the remaining portion forming a flap to fold around the pockets, and fastening devices extending through the pockets and 10 each including an internally threaded tubu-

lar member and a threaded pin engaging in the tubular member and said tubular member and pin being respectively formed with lateral heads at their outer ends, said fastening devices constituting pivots for keys 15 within the pockets and adjustable longitudinally.

In testimony whereof, I affix my signature.

JAMES S. WARNER. [L. s.]
